UNITED STATES PATENT OFFICE.

ARTHUR B. TAYLOR, OF NEWARK, NEW JERSEY, ASSIGNOR TO BAKER & COMPANY, INC., A CORPORATION OF NEW JERSEY.

SELF-LOADING MAGAZINE PENCIL.

Application filed April 1, 1921. Serial No. 457,749.

To all whom it may concern:

Be it known that I, ARTHUR B. TAYLOR, a citizen of the United States, and a resident of Newark, in the county of Essex 5 and State of New Jersey, have invented new and useful Improvements in Self-Loading Magazine Pencils, of which the following is a specification.

This invention relates in general to pencils 10 of the type comprising a holder or casing from which a length of lead may be progressively ejected or propelled as the writing point wears away or breaks off. More particularly the invention relates to pencils of 15 this character having a magazine to receive a plurality of leads which may be successively brought into writing position as the preceding lead is consumed.

The objects of the invention are to provide 20 a propelling or "self-sharpening" pencil comprising a casing having an opening in one end thereof for the ejection of a lead, an ejecting mechanism for forcing the lead through said opening, and a magazine to receive 25 a plurality of leads arranged between said opening and said ejecting mechanism and having a channel or groove in the bottom thereof in substantial alinement with said opening to receive only one lead at a 30 time, the leads falling by gravity into said groove to be propelled by said ejecting mechanism through said opening; to provide a magazine of improved construction; to provide an improved combination of the magazine 35 and ejecting mechanism whereby the magazine is always in proper relation to the ejecting mechanism, thus ensuring proper operation of the pencil in unskilled hands; to provide improved storage compartments 40 for reserve supplies of leads in addition to the magazine; to provide a construction whereby the leads can be easily and quickly transferred from said storage compartments to said magazine, and to obtain other results 45 and advantages as may be brought out by the following description.

Referring to the accompanying drawings, in which like numerals of reference indicate the same parts throughout the several views, 50 Figure 1 is a longitudinal sectional view through a self-feeding pencil constructed in accordance with my invention;

Figure 2 is a transverse sectional view taken on the line 2—2 of Fig. 1, and looking 55 in the direction of the arrows;

Figure 3 is a detached perspective view of the magazine, portions being broken away;

Figure 4 is a detail perspective view of the sheet metal member forming part of the magazine;

Figure 5 is an end view of the pencil with the lead holding and guiding tip removed;

Figure 6 is a transverse sectional view through the magazine taken on the line 6—6 of Fig. 3, and

Figure 7 is a view similar to Figure 6 showing a magazine for use with a cylindrical casing.

In the embodiment of my invention shown in the drawings, the reference character A 70 designates a tubular casing one end of which is normally closed by a removable lead holding and guiding tip B having an axial opening 1 to receive a piece of lead 2 from a magazine C arranged in the casing between 75 the tip B and lead ejecting or propelling mechanism D mounted in the other end of the casing. The casing A may be of any desired cross-sectional configuration, but in the present instance I have shown it hexagonal 80 and having one end formed with a circular portion 3 to receive the adjacent end of the cross-sectionally circular tip B, as shown in Figure 1.

The magazine C is constructed to receive 85 a plurality of leads 2, and, when the pencil is held horizontally in proper position, to deposit said leads singly by the action of gravity each into a position in substantial alinement with the opening 1 in the tip B, 90 so that it may be ejected by the mechanism D into writing position. To accomplish this result in the construction shown in the drawings, the magazine C is substantially V-shaped in cross-section, having downwardly 95 converging sides 4 along which the leads roll by gravity, in feeding, said sides terminating at their adjacent ends in a groove 5 of a size to receive only one of the leads 2 at a time. When this magazine is in place 100 in the pencil, its end next the tip B, as 6, is closed only by said tip, while the other end thereof is permanently closed, as at 7, to prevent displacement of the leads. The magazine is of a length slightly greater than 105 that of the leads 2, and is fitted into the casing A so that the sides 4 of the magazine form with the wall of the casing a chamber for the reception of leads 2, which may be inserted therein through the open 110

end of the casing and magazine when the tip B is removed. The underside of the magazine C is also formed with a longitudinal wing or rib 8 to cooperate with the sides

5 4 to properly position and support the magazine in the casing, said wing also forming with the casing A storage compartments 9 for receiving reserve supplies of the leads, as shown in Figures 2 and 3.

10 The groove 5 in the magazine is also arranged in substantial alinement with an ejecting or propelling rod 10 of the mechanism D, adapted to slide in said groove 5 of the magazine and be reciprocated by a
15 screw sleeve 11 rotatably mounted axially of the casing A in a tubular bearing 12 fixed on the interior of the casing at its end opposite the tip B, said sleeve engaging a threaded head 13 on the rod 10 to force the lead 20 outwardly from the magazine through the opening 1 in the tip B into writing position. The screw sleeve 11 is provided with an operating head 14 projecting from the end of the casing at the outer end of the tubular
25 bearing 12, and at the inner end of said bearing is a collar 141 fast on the sleeve, so that it can be rotated by the head 14 without any longitudinal movement.

In constructing the pencil I preferably utilize a tube 15 of a length substantially equal to the combined lengths of the magazine C and the ejecting or propelling rod 10 and having an internal diameter slightly greater than the diameter of the leads 2. One end of this tube is threaded for a short distance, as at 16, to receive the tip B, and at the inner end of said threaded portion the wall of the tube is cut away, as at 17, Figure 3, substantially the length of one of the leads 2 to form the slot 5 at the bottom of the magazine. This tube receives the ejecting or propelling rod 10 and extends inside the screw sleeve 11, said rod having at its end away from the magazine a lateral fin 13 which projects slidably through a slot 18 in the wall of the tube 15, and is shaped at its outer edge to engage the interior threads of the screw sleeve 11 and thus be propelled by rotation of the latter. At the inner end of the magazine C a collar 19 is fixed upon the tube 15, said collar being of a size and configuration to fit within the casing A and being secured thereto, as by a pin 23, said collar forming the closed end 7 of the magazine. Preferably the magazine C is made from a strip of sheet metal 20, of the same length as the slot 17, bent on its longitudinal center and returned upon itself to form the wing 8, the sides of said strip being then curved outwardly apart, as at 21, to slip over the tube 15 between the collar 19 and the threaded end 16, and then bent outwardly at an angle to each other to form the sides 4 of the magazine, as shown in Figures 3 and 4. The strip 20 thus shaped is preferably

soldered or otherwise rigidly connected to the tube 15 and collar 19, and the wing 8 and sides 4 serve as centering supports for the magazine in the casing.

In use of my improved pencil, the tip B 70 is removed and the magazine and storage chambers 9 filled with leads; then the tip is replaced, and the propelling rod 10 being retracted clear out of the magazine, the pencil is held horizontal with the magazine 75 B in the position shown in Figure 2, so that a lead will fall by gravity into the groove 5. Some exterior indicating means is provided so that the user may know when the magazine is in proper feeding position, such 80 for example as a usual pocket clip 24 secured to the casing so that when uppermost the magazine is in feeding position. When a lead has fed into the slot 5, which can be facilitated by tapping the pencil gently, the 85 propelling rod 10 is advanced to expose the extremity of the lead for use, as is common in pencils of the lead-propelling type. To replenish the leads in the magazine C it is merely necessary to remove the tip A and 90 transfer leads from the storage compartments 9 or elsewhere to the magazine.

In Figures 2, 3, 5 and 6 I have shown the collar 19 hexagonal to fit a hexagonal casing, but the collar may be made in any shape to fit a particular casing, such for instance as the collar 22 shown in Figure 7 which is designed for a casing circular in cross-section. 95

While I have shown and described one possible embodiment of my invention it will be understood that this is only for the purpose of illustrating the principles thereof, and that many modifications and changes can be made in the detail construction of the invention without departing from the spirit or scope of the invention. Therefore, I do not desire to be understood as limiting myself except as required by the following claims when construed in the light of the prior art. 110

Having thus described the invention, what I claim is:

1. In a pencil of the character described, the combination with a casing having an axial opening therein to receive a lead, of a magazine in said casing to receive a plurality of leads, said magazine comprising a tube having an internal diameter slightly greater than the diameter of said leads and having its walls cut away at one side to form a slot substantially equal in length to said leads, and a plurality of longitudinal wings projecting radially from said tube to support said tube in said casing in axial alignment with said opening, two adjacent ones of said wings being arranged on opposite sides of said slot to receive said leads therebetween and direct the leads into said slot.

2. In a pencil of the character described 130

the combination of a casing, a longitudinally slotted tube mounted in said casing and forming a passageway for a lead, a propelling rod in said passageway having a 5 lateral head projecting through the slot, a screw sleeve inclosing said tube and engaging said head, a tubular bearing for said screw sleeve held against longitudinal movement in said casing, a stop on the screw 10 sleeve at the inner end of said bearing, and an operating head on said screw sleeve at the other end of said bearing and outside of said casing, said head and stop engaging said tubular bearing to hold said screw 15 sleeve against longitudinal movement in said casing.

3. In a pencil of the character described,

the combination with a casing, of a magazine in said casing to receive a plurality of leads, said magazine comprising a tube having an internal diameter slightly greater than the diameter of said leads and having its walls cut away at one side to form a slot substantially equal in length to said leads, and a member secured exteriorly of said 25 tube comprising a piece of sheet material returned longitudinally upon itself for a portion of its width with its sides curved outwardly to receive said tube and diverging outwardly on opposite sides of said slot, 30 said outwardly diverging sides being adapted to receive the said leads between them and guide them into said slot.

ARTHUR B. TAYLOR.
